UNITED STATES PATENT OFFICE

ROSS J. RINK, OF STAPLES, MINNESOTA

GARMENT HANGER

Application filed June 20, 1932. Serial No. 612,325.

This invention relates to garment hangers and has for its object the provision of a hanger which may be easily attached to or removed from a garment and which will furnish a firm support for the garment when engaged over a coat hook or other device. The invention is illustrated in the accompanying drawing and consists in certain novel features which will be hereinafter fully disclosed.

In the drawing, Fig. 1 is an elevation of my improved garment hanger showing it applied to the collar portion of a garment.

Fig. 2 is a section on the line 2—2 of Fig. 1.

Fig. 3 is a section on the line 3—3 of Fig. 1.

In carrying out the invention there is provided an attaching pin which is constructed from a single strand of wire bent so as to define a piercing member 1 having a pointed end, as shown at 2, adapted to penetrate the fabric of the garment collar. At the end of the piercing member 1, remote from the point 2, the wire or light rod is formed into a coil 3 and from the coil an upper member 4 extends in the same general direction as the piercing member 1. At a point adjacent the pointed tip 2, the strand 4 is formed into a second coil 5 from which depends a hook 6 in which the point 2 may be engaged after it has passed through the fabric of a garment collar, as will be understood upon reference to Fig. 1, the hook 6 constituting a keeper for the point 2 so that it will be locked in engagement with the fabric of the garment and will be held close to the fabric so that it will not subject the wearer of the garment to any discomfort. The hook 6 is provided with a round end by doubling the strand, as at 12, and then continuing the wire upward, as at 16, to terminate in an eye 17 encircling the upper member 4. Sharp corners are thus avoided and a brace 45 is provided to prevent spreading of the mem-

bers 1 and 4 when the device is in use. Engaged through the coils 3 and 5 are hanger loops 7 which, as shown most clearly in Figs. 2 and 3, are substantially triangular in contour, the apexes of the triangles being inverted and engaged through the respective coils while the bases of the triangles are received within hems or folds 8 at the ends of a strap 9 which may be of cloth, leather or other material. By lapping the ends of the strap around the bases of the triangular hangers and securing the ends, as indicated, by rivets or other fasteners 10, the strap will be held in a flat condition so that it may be readily engaged over a peg or hook upon a rack or tree.

The device is very light and may be readily applied to any garment. When the garment is outworn and discarded, the hanger may be removed and readily applied to some other garment or, if desired, it may be detached and applied to the garment only when the latter is to be suspended, thereby avoiding any possible discomfort to the wearer of the garment. The device may, of course, be made in various sizes so as to be adapted to the size, weight or material of all garments.

Having thus described the invention, I claim:

1. A garment hanger comprising a garment-engaging member having a piercing portion and a keeper portion to retain the piercing portion in engagement with a garment, a keeper hook depending from the keeper portion, a brace forming a connection between the keeper hook and keeper portion, hanger loops engaged with the garment-engaging member, and a strap attached to and extending between the loops.

2. A garment hanger comprising a garment-engaging member of integral construction including a piercing member having a pointed end and a keeper member connected with the piercing member at one end by a

coil and provided with a second coil adjacent the pointed end of the piercing member and a keeper hook depending from the second coil and engaged with the end of the piercing member, hanger loops of triangular form engaged through the coils of the garment-engaging member, and a suspending strap having its ends lapped around the bases of the respective loops, the extremities of the strap being secured to the intermediate portion of the same at the inner sides of the loops.

In testimony whereof I affix my signature.
